Patented June 12, 1900.

B. B. McDANIEL.

METHOD OF STRINGING PIANOFORTES,

(Application filed Sept. 28, 1898.)

(No Model.)

UNITED STATES PATENT OFFICE.

BENJAMIN B. McDANIEL, OF DES PLAINES, ILLINOIS.

METHOD OF STRINGING PIANOFORTES.

SPECIFICATION forming part of Letters Patent No. 651,765, dated June 12, 1900.

Application filed September 23, 1899. Serial No. 731,435. (No model.)

To all whom it may concern:

Be it known that I, BENJAMIN B. McDANIEL, a citizen of the United States, residing at Des Plaines, in the county of Cook and State 5 of Illinois, have invented certain new and useful Improvements in Methods of Stringing Pianofortes and Like Musical Instruments; and I do hereby declare the following to be a full, clear, and exact description of the invention, 10 such as will enable others skilled in the art to which it appertains to make and use the same.

Stringed musical instruments having unison strings require frequent tuning to maintain the required pitch. Particularly is this 15 the case with instruments having three or more unison strings to each note. As generally arranged the three unison strings of adjacent notes in the chromatic scale have the third string of each note formed of the same 20 element, wire, or string doubled upon itself, the part forming the third string of one note being under a different tension from the part forming the first string of the next note in order. The parts of the same string being under 25 different tension results in the difficulty experienced in keeping the instrument in tune, because there is a tendency for the main string to slip at the bight around the hitch-pin, thereby loosening the tension of one half 30 and proportionately increasing the tension of the other half, which throws both out of tune. This invention requires each note to have four, six, or an even number of unison strings to each note, all the unison strings being of substantially 35 equal length and tension and corresponding strings being formed of folded parts of the same string. By this method of stringing pianofortes and like musical instruments the same will remain in tune for a greater length of time, the quality, volume, and character of the tone are improved, and parts of the same string will not be under different tension and the work of tuning greatly simplified.

45 The drawing is typical of the class of stringed musical instruments for which the invention is designed.

The sounding-board 1 is provided with the spaced bridges 2 and 3, over which the unison strings pass. The wrest-plate 4 and hitch-plate 5 receive the wrest-pins 7 and the hitch-pins 6, respectively.

It will be observed that the unison strings of each note are in even number, being a multiple of two, four being shown, and of equal 55 length. Hence the tension of the unison strings is uniform and equal. Each note is composed of four unison strings, which are parts of two main strings folded upon themselves, the hitch-pins being received in the 60 bights and the terminals being attached to corresponding wrest-pins.

The pins are provided in two sets, inner and outer, and corresponding hitch-pins aline longitudinally, the inner hitch-pin being of less 65 diameter than the outer hitch-pin to properly space the unison strings. The same result would be attained by doubling the outer hitch-pins. Corresponding hitch-pins and wrest-pins are spaced apart a like distance to enable 70 the unison strings of any one note being of equal length.

The inner unison strings 8 are hitched to the inner pins 6 and have their terminals applied to the outer wrest-pins 7, and the outer 75 unison strings 9 are attached to the outermost hitch-pins and have their extremities secured to the inner wrest-pins.

From the foregoing it will be seen that the parts of the same and corresponding unison 80 strings are under like tension. Hence there is no tendency for equalization of differently-tensioned strings, which is the chief source of trouble in maintaining stringed musical instruments of the class having unison strings 85 in tune. Moreover, the strings are not so liable to break and the tuning is greatly simplified and facilitated.

It is to be understood that in applying the invention to instruments having two unison 90 strings the latter will be of equal length and tension, the main string being doubled upon itself at a central point.

Having thus described the invention, what is claimed as new is—

1. In stringed musical instruments, pairs 95 of wrest-pins longitudinally spaced, the outermost pins being opposite the space between the innermost pins and spaced a less distance apart, longitudinally-spaced hitch-pins, and musical strings looped around the hitch-pins and having their terminals attached to corresponding wrest-pins and forming multiple 100 unison strings, the folded portions of each

string being of equal length and tension, substantially as described.

2. In stringed musical instruments, longitudinally-spaced hitch-pins, pairs of wrest-pins spaced apart a distance equal to the distance between the hitch-pins, the pins of the pairs being unequally spaced, and musical strings looped around the hitch-pins and having their terminals attached to the wrest-pins to form unison strings of equal length and

tension, the outer string being folded around the inner folded string, substantially as described.

In testimony whereof I affix my signature in presence of two witnesses.

BENJAMIN B. McDANIEL. [L. S.]
